BENJAMIN F. WEISHAMPEL, OF BALTIMORE, MARYLAND.

Letters Patent No. 85,773, dated January 12, 1869.

IMPROVEMENT IN DEVICES FOR SECURING FASTENING-LOOPS TO NECK-TIES.

The Schedule referred to in these Letters Patent and making part of the same.

To all whom it may concern:

Be it known that I, BENJAMIN F. WEISHAMPEL, of Baltimore, in the county of Baltimore, and State of Maryland, have invented a new and improved Fastening for Neck-Ties; and I do hereby declare that the following is a full, clear, and exact description thereof, reference being had to the accompanying drawings, making a part of this specification, in which—

Figure 1 is a perspective view of a neck-tie, showing the improved fastening applied to the back part of its pad.

Figure 2 is a front view of a portion of a neck-tie pad, showing the spurs of the fastening inserted through it, and bent over.

Figure 3 is an enlarged perspective view of the fastening, detached from a neck-tie.

Figures 4, 5, 6, 7, 8, and 9, are perspective views of several modifications of the improved fastening.

Similar letters of reference indicate corresponding parts in the several figures.

This invention relates to a new and useful improvement, which is applicable to neck-ties or bows known as "butterfly-ties," and which is designed for holding securely the elastic loops by which these ties or bows are fastened to the front buttons on shirt-collar bands.

Previous to my invention, various metallic devices have been contrived for fastening the elastic loop to neck-bows or ties, and in one instance a concave button, with a hole at its back and front ends, has been adopted; but these devices do not answer the purpose as well as mine, for the reason that some of them permanently attach the loop, and where this is not the case, the inconvenience attending the detaching of it is much greater than is desirable.

The object of my invention is to provide a neck-tie with a device which will admit of the ready attachment to it and detachment from it of an elastic loop, so that when a loop breaks or becomes useless from any cause, it can be detached from the tie, and another loop conveniently substituted in its stead, as will be hereinafter explained.

To enable others skilled in the art to understand my invention, I will describe its construction and operation.

In the accompanying drawings, fig. 1, I have represented one form of my improved fastening, applied to the back of the pad A of a neck-tie, B, which may be

made of cloth, paper, or other suitable material, in the usual manner. This fastening is made of a piece of sheet-metal, shaped so as to form a shield, A', through one end of which a hole, a, is made, and from the edges of which spurs b b extend.

When the shield is fastened to the back of pad A, by inserting spurs b b through it, and bending them down, as shown in fig. 2, it affords a ready means of attaching an elastic loop, D, to the tie-pad, which is done by passing the loop down through the shield, and through hole a, and drawing the knotted ends of this loop into the shield, as clearly shown in fig. 3.

When the loop D breaks or wears out, it can be readily detached from the shield, and a new loop substituted in its stead.

In figs. 4, 5, 6, 7, 8, and 9, different forms of shields A' are represented, having fastening-spurs b formed on them, and provided with eyes for receiving and holding the elastic loops. Any one of these modifications will answer the purpose of holding the elastic loops, and allowing them to be detached at pleasure. In practice, the fastenings will be made by stamping and shaping-machinery, suitably adapted to the purpose, so that they can be made and furnished to the market at a very small cost. Being made of a single piece of metal, there will be no hand-labor required in finishing them, and having spurs b b formed on their edges, they can be quickly fastened securely to the pads of neck-ties or scarfs.

I do not claim a self-fastening metallic device for confining an elastic loop of a neck-tie or bow, when it is not made with a larger entrance or hole at its upper end than is made at the end where the loop is protruded from the fastening; therefore,

What I do claim as my invention, and desire to secure by Letters Patent, is—

1. The metallic self-fastening device A' b a, figs. 1, 2, 3, 4, 5, and 6, when made with a flaring entrance and a contracted holding-end, as described and shown.

2. The construction of the metallic fastening A', as shown in fig. 7, to wit, with open sides and back, and a small opening, a, for the purpose described.

BENJ. F. WEISHAMPEL.
